TENNIS BALL HOLDER

Albert W. Stein, Hillside, N. J.

Application September 17, 1936, Serial No. 101,183

7 Claims. (Cl. 248—205)

This invention relates to tennis ball containers and more particularly to a container adapted to be carried by a tennis racket press.

It is customary, in playing tennis, for each player to carry, in addition to the tennis racket and racket press, three tennis balls. Heretofore, the tennis balls have been carried by hand, which was inconvenient, or have been carried in a fabric pocket of a fabric tennis racket cover, where the tennis balls are subjected to being easily crushed and mutilated.

It is an object of my invention to provide a protective tennis ball container made of metal, having semi-spherical ends to conform to the configuration of the tennis balls, and to provide a holder for removably securing the protective tennis ball container to the tennis racket press.

A further object of my invention is to provide a holder of the class described having integral means to enable it to be secured, with equal efficiency, to racket presses of various dimensions.

A further object of my invention is to provide a holder for tennis ball containers comprising two spring clip members provided with arms removably secured to the racket press bolts, the spring clip members being removably and adjustably secured together by any suitable means.

These and other advantageous objects, which will later appear, are accomplished by the simple and practical construction and arrangement of parts hereinafter described and exhibited in the accompanying drawing, forming part hereof, and in which:

Fig. 1 is a side elevational view of a device made in accordance with my invention, shown applied to a tennis racket press,

Fig. 2 is a perspective view of my device, Fig. 3 is a longitudinal vertical sectional view taken on lines 3—3 of Fig. 2,

Fig. 4 is a perspective view of a modified form of the invention,

Fig. 5 is a side elevational view, partly in section, of a further modification of the invention,

Fig. 6 is a perspective view of one of the spring clip members used in the form of invention shown in Fig. 5, and,

Fig. 7 is a transverse sectional view taken on line 7—7 of Fig. 1,

Fig. 8 is a side elevational view, partly in section, of a further modified form of the invention, and

Fig. 9 is an end view of the same.

Referring to the drawing, in Fig. 2 the device is shown to comprise two interchangeable spring clips 8—8, each of which has a pair of arms 9

pivoted thereto at 10, the free ends 11 of the arms being secured to the corners of a tennis racket press 12 by thumb screws 13 of the racket press bolts 14. The spring clips 8—8 are provided with downwardly directed flanges 15 (see Fig. 3) through which a tie rod 16 passes, the tie rod having a head 17 abutting the flange 15 of one spring clip and the other end of the tie rod 16 being threadedly engaged by a nut 18 engaging the flange 15 of the other spring clip. By this arrangement, the device is adjustable and can be applied with equal efficacy to racket presses of various dimensions, and the tie rod will at all times firmly secure the spring clips together.

A tennis ball container 19 is adapted to be snapped into the spring clips 8 and will be firmly held in that position (Figs. 1 and 7) until manually withdrawn.

In the modification illustrated in Fig. 4, the tie rod 16 is dispensed with and a single, elongated spring clip 28 is used, said clip having arms 29 pivoted thereto at 30, the apertured ends 31 of the arms being secured to the corners of the racket press by the racket press thumb screws 13 as with the structure shown in Fig. 2, or may be secured directly to the racket press by passing screws through the apertures 31.

As clearly shown in Fig. 3, the tennis ball container preferably comprises the elongated cylindrical body 32 having a semi-spherical end 33 conforming to the spherical configuration of the tennis balls, and having an open end 34 which is closed by a cover 35 removably secured to the container body 32 in any desired or convenient manner. The cover 35, like the end 33 of the container body, is semi-spherical to conform to the configuration of the tennis balls. The construction described reduces to an absolute minimum the amount of free space, and therefore the amount of air, within the container, thereby preserving the resiliency and spherical configuration of the tennis balls held in said container. The tennis balls are also protected from injury and are instantly available by either removing the container itself from the spring clips 8 or by removing the cover 35 of the container.

In the modification shown in Figs. 5 and 6, the spring clip 8 is provided with an end clip 36. With this form of spring clip it is possible to use the ordinary commercial tennis ball container, which has a flat end 37. The commercial tennis ball container also has a flat top member which is discarded when the metal seal of the container is broken, in originally removing the

55

tennis balls. The container then has an open end 38 and by resting the flat end 37 of the container against the end clip 36 of one spring clip 8, and allowing the end tennis ball within 5 the container to rest against the end clip 36 of the other spring clip, the tennis balls and container will be held firmly in place on the racket press.

The form of invention shown in Fig. 8 is like 10 that shown in Fig. 5 except that only one spring clip 8 is used; instead of a second spring clip 8 there is provided a rigid end member 40 having 15 a peripheral flange 41 and having depending flanges 42 to receive the tie-rod 16. The open end 38 of the tennis ball container is received within the peripheral flange 41 of the end member 40, and the flat, closed end 37 of the container is snapped into the spring clip 8. By this arrangement the normally open end 38 of the container is closed.

By means of this construction, the ordinary 20 commercial tennis ball container, after the cover has been removed, can be permanently utilized as a tennis ball container.

From the foregoing description it will be seen 25 that I have provided a device for holding tennis balls which can be readily attached to standard types of tennis racket presses and I have provided a container for the tennis balls which is 30 constructed to hold a plurality of tennis balls in their proper spherical shape, and to maintain their resiliency by reducing to an absolute minimum the amount of air in the container.

The foregoing disclosure is to be regarded as 35 descriptive and illustrative only, and not as restrictive or limitative of the invention of which obviously embodiments may be constructed, including many modifications, without departing from the general scope herein indicated and 40 noted in the appended claims.

Having thus described my invention, what I claim as new and desire to secure by Letters Patent, is:

1. A holder for tennis ball containers comprising a spring clip, and arms pivotally secured to 5 said clip the free ends of said arms being adapted to be secured to a tennis racket press.

2. A holder for tennis ball containers comprising spring clips, arms pivotally secured to said 10 clips the free ends of said arms being adapted to be secured to a tennis racket press, and means carried by said spring clips for adjustably securing said clips together.

3. A holder for tennis ball containers comprising 15 spring clips, said clips having flanges, means for securing said clips to a tennis racket press, and means carried by the flanges of said clips for adjustably securing said clips together.

4. A holder for tennis ball containers comprising 20 spring clips, said clips having flanges, means for securing said clips to a tennis racket press, and bolt means engaging the flanges of said clips for adjustably securing said clips together.

5. A holder for tennis ball containers comprising 25 spring clips, adapted to engage opposite sides of a tennis ball container, said spring clips being provided with end clip members adapted to engage the ends of a tennis ball container.

6. A holder for tennis ball containers comprising 30 spring clips, means for securing said clips to a tennis racket press, and means for adjustably securing said clips together.

7. A holder for tennis ball containers comprising 35 spring clips, adapted to engage opposite sides of a tennis ball container, said spring clips being provided with end members adapted to engage the ends of a tennis ball container.

ALBERT W. STEIN.
